COMBINATION SELF-SERVICE DISPENSER AND STORAGE FOR EDIBLES

Clyde R. Rockriver, Los Angeles, Calif.

Application March 23, 1950, Serial No. 8,707

Term of patent 14 years

(Cl. D52—2)

To all whom it may concern:

Be it known that I, Clyde R. Rockriver, a citizen of the United States, residing in Los Angeles, in the county of Los Angeles and State of California, have invented a new, original, and ornamental Design for a Combination Self-Service Dispenser and Storage for Edibles, of which the following is a specification, reference being had to the accompanying drawing forming a part thereof.

In the drawing:

Figure 1 is a front perspective view of a combination self-service dispenser and storage for edibles, showing my new design;

Fig. 2 is a side elevational view; and

Fig. 3 is a rear view.

I claim:

The ornamental design for a combination self-service dispenser and storage for edibles, substantially as shown.

CLYDE R. ROCKRIVER.
